JAMES S. WHITNEY, OF LOWELL, MASSACHUSETTS.

Letters Patent No. 102,344, dated April 26, 1870.

IMPROVED CURTAIN-FIXTURE.

The Schedule referred to in these Letters Patent and making part of the same.

To all whom it may concern:

Be it known that I, JAMES S. WHITNEY, of Lowell, in the county of Middlesex and State of Massachusetts, have invented certain new and useful Improvements in Curtain-Fixtures, of which the following is a full, clear, and exact description; reference being had to the accompanying drawings making part of this specification, in which—

Figure 1 represents a central sectional elevation, and

Figure 2 an end view, both considerably enlarged.

This invention relates to that class of curtain-fixtures which is self-winding, by means of a concealed spiral spring wound around a central rod, A.

In constructing my said curtain-fixture, a concave or recessed pulley B, or a band, is fitted onto one end of the roll C, the rim e projecting outward, or outward and inward, from the central head b, and smoothly finished as usual.

On the center pintle D, or formed in solid connection therewith, is a recessed or chambered bolt-socket, g, and through this I insert a bolt, h, which is pro-

vided with a foot or friction-pad, g', curved on its outer surface, corresponding with the inside of the pulley- rim or band e.

Within the bolt-socket and around the bolt I arrange a spiral spring, 4, which actuates the bolt in one direction to cause the foot g' to press against the inner surface of the rim e, and hold the latter and the roll from turning.

To release the bolt or the foot g', and allow the concealed spring to wind up the curtain, I pull a cord, E, attached to the lower end of the bolt, and draw the bolt downward.

I claim—

The curved foot g' in combination with the sliding spring bolt h, and with the rim or band e, all arranged and operating in the manner and for the purpose described.

J. S. WHITNEY.
